UNITED STATES PATENT OFFICE.

HENRY NEWTON JAMES, OF MIAMI, FLORIDA.

SCISSORS AND SHEARS.

Application filed April 18, 1925. Serial No. 24,266.

This invention relates to hand cutting and gripping tools and has special reference to a combination scissors tool.

More particularly the invention relates to a combination of scissors, wire cutter, needle or pin holder and article grip.

One object of the invention is to improve the general construction of devices of this character.

10 A second object of the invention is to provide a tool having a pair of pivoted scissor members provided with needle grips of varying sizes.

15 A third object of the invention is to provide a scissors device having needle gripping surfaces on the handles adjacent the pivoted portions.

With the above and other objects in view, the invention consists in general of certain 20 novel details of construction and combinations of parts hereinafter fully described, illustrated in the accompanying drawings and specifically claimed.

In the accompanying drawings like characters of reference indicate like parts in 25 these several views, and:—

Fig. 1 is a side view of a pair of scissors in closed position as constructed in accordance with this invention;

30 Fig. 2 is a view similar to Fig. 1 showing the scissors in open position; and

Fig. 3 is an enlarged section on the line 3—3 of Fig. 1.

As shown in the present embodiment the invention consists of a pair of scissors members 35 consisting each of a blade portion 10 of ordinary scissors formation and a shank portion 11 having a finger eye 12 at the end thereof. These blade portions are pivotally connected 40 between the blades and shanks by a pivot 13.

Between the pivot 13 and the respective finger eyes 12 each shank has adjacent the

pivot a wire-cutting notch 14, while spaced therefrom in the direction of the eyes, each shank has a plurality of article gripping 45 notches 15 graduated in size and having the notches on one shank arranged in similarly graduated cooperative relation to the notches in the remaining shank. Adjacent the notches 15 the shanks are provided with cooperating roughened jaws 16 such as may be produced by the formation of file teeth or nurling.

It will be noted that the wire-cutting jaws are larger than the largest of the gripping jaws so that the wire cutters may also serve as grippers for larger wires than can be gripped in the jaws 15.

In use it can be readily seen that the implement may be used, if desired, as an ordinary pair of scissors, or may be used to cut wire by the employment of the jaws or notches 14. Still further the jaws or notches 15 may be used to grip such articles as needles or the like, the proper size of the 60 graduated grips being selected for the special article to be gripped. Moreover articles of various sizes may be gripped between the roughened or nurlled jaws.

There has thus been provided a simple 70 and efficient device of the kind described and for the purpose specified.

Having thus described the invention, what is claimed as new is:—

In combination, a pair of members pivot- 75 ally connected and having overlapping edges, the overlapping edges being provided with opposed rectangular notches, the bottoms of said notches being beveled to form opposed cutting edges, and the sides of the 80 notches projecting beyond the cutting edges whereby to prevent slipping of an article being cut.

HENRY NEWTON JAMES.
